UNITED STATES PATENT OFFICE.

CHARLES TUCKFIELD, OF EAST MOLESEY, ENGLAND, ASSIGNOR OF TWO-THIRDS TO DYSON WESTON, OF LONDON, ENGLAND.

ROTARY ENGINE.

SPECIFICATION forming part of Letters Patent No. 703,502, dated July 1, 1902.

Application filed November 15, 1901. Serial No. 82,388. (No model.)

To all whom it may concern.

Be it known that I, CHARLES TUCKFIELD, a subject of the King of Great Britain, residing at 12 Palace Crescent, East Molesey, Surrey, England, have invented new and useful Improvements in Rotary Engines, of which the following is a specification.

This invention relates to improvements in rotary engines, the improvements being applicable to both high-pressure and compound rotary engines.

According to the invention I provide a casing or cylinder having a drum which fits therein and is mounted upon a shaft passing through the covers or ends thereof. This drum is formed with one or more peripheral grooves, which, however, do not extend completely around the drum, so that the annular chambers which are thereby formed are stopped at one point. In conjunction with each of the grooves, which are of a suitable shape in cross-section, such as half-round or taper, I arrange a similarly-shaped sliding abutment or piston, which fits into the groove and is held therein, preferably, by the pressure of steam behind it. Ports open into each groove on either side of the aforesaid sliding abutment, so that when steam is admitted through one port the drum is driven around, the steam escaping through the other port after the stop in the groove has passed the abutment. Sufficient space is advantageously left between the consecutive grooves to permit of the insertion of packing-rings.

In practice I find it advantageous to construct an engine which can be employed either as a high-pressure engine or as a compound engine, and in this case a suitable form of distributing-valve is fitted to the motor to enable the change to be effected.

In the accompanying drawings I have illustrated by way of example my improvements applied to a motor which can be employed as a high-pressure motor or as a compound motor.

In the said drawings, Figure 1 is a longitudinal section of the motor. Fig. 2 is a vertical transverse section thereof. Fig. 3 is a plan of the motor with the valve-cover and valve removed. Fig. 4 is a section of the

valve similar to that shown in Fig. 2, but 50 showing it in a different position; and Fig. 5 is a section of the compound piston or drum.

a is the casing or cylinder, and *b* is the drum, which is mounted upon the shaft *b'*, passing through stuffing-boxes in the covers 55 *a' a'* of the cylinder.

c c' d d' are four peripheral grooves which are formed in the said drum *b*, the said grooves being shown taper in cross-section and forming peripheral steam-passages, which, however, do not extend completely around the drum, as the grooves stop at one point, as clearly shown at *e*, Figs. 2 and 5.

ff are the abutments, which are of a shape to conform to that of the peripheral grooves 65 and which work in recesses *g* in the cylinder *a*, being held in contact with the bottoms of the grooves by the pressure of steam admitted to the recesses *g g* behind them through the passages *h*. (See Fig. 2.) 70

i i' are steam-inlet ports, and *j j'* exhaust-ports.

k is a valve-chest which is provided upon the top of the cylinder, and *l* is the valve which works in the valve-chest *k*. This valve *l* is 75 provided with two longitudinal passages *m* and *n*, respectively, which serve as inlet-ports for the steam, and with two exhaust-passages *o* and *p*.

When the valve is placed in the position indicated in Fig. 2, the engine operates as a compound engine, the steam entering the steam-chest through the pipe *q*, thence passing down the inlet-ports *i i'* and entering the peripheral chambers *c c'*, driving around the 85 shaft *b'* until the stops *e e* pass the abutments *ff* in these two peripheral grooves, when the steam behind the said stops escapes through the ports *j j'*, flows through the passages *m n*, respectively, and thence through the ports *i i'* 90 to the larger peripheral grooves *d d'*, from which it ultimately escapes through the outlet-ports *i' i'* and passages *o p* to the main exhaust *r*, provided in the cylinder.

When the valve is in the position indicated 95 in Fig. 4, the steam enters the ports *i i'* and *i' i'* directly to both sets of grooves, so that the engine then works as a high-pressure engine,

not exhausting from the grooves $c c'$ to the grooves $d d'$.

The valve can be adjusted in position by suitable means, and in the drawings is shown 5 controlled by the rod s , which passes through a stuffing - box in the valve-chest k and is hinged to an operating-lever t , pivoted at t' to the bracket u upon the cylinder of the motor.

Having now particularly described and as- 10 certained the nature of my said invention and in what manner the same is to be performed, I declare that what I claim is—

1. In a rotary motor, the combination with a cylinder, of a drum having one or more ec- 15 centric tapered peripheral grooves formed therein, each groove being stopped at one point and of one or more sliding abutments

engaging the said groove or grooves, substan- tially as described.

2. In a rotary motor, the combination of a 20 cylinder, of a drum keyed upon a shaft jour- naled in the cylinder, of a number of eccen- tric peripheral grooves formed in the drum the said grooves being stopped or closed at one point, of sliding abutments engaging 25 each groove and of a compound-passage slide distributing-valve and ports whereby the motor can be operated as a high-pressure or as a compound motor, substantially as described.

CHARLES TUCKFIELD.
